UNITED STATES PATENT OFFICE

LYTLE S. ADAMS, OF SEATTLE, WASHINGTON, ASSIGNOR TO AIRWAYS PATENT CORPORATION, A CORPORATION OF DELAWARE

GRAPPLE FOR AIRPLANE PACKAGE TRANSFER APPARATUS

Application filed May 10, 1929. Serial No. 361,957.

This invention relates to package transfer apparatus of the type disclosed in my pending application Ser. No. 305,970, filed September 14, 1928, now Patent No. 1,818,835, issued Aug. 11, 1931, wherein the airplane is provided with a trailing suspension cable for lowering and lifting the package carrier and suitable grapple means for automatically disconnecting one carrier and attaching another 10 at a transfer station.

The invention aims to improve the grapple means to insure reliability for performance under varying conditions of operation.

Other aims and advantages of the invention 15 appear in connection with the following description of the preferred embodiment illustrated in the accompanying drawings, wherein

Fig. 1 is a side view of the cable receiving or 20 socket member, which forms one of the members of the grapple device;

Fig. 2 is a longitudinal section, and Fig. 3 is a cross-section of the same on the lines 25 2-2 in Fig. 1 and 3-3 in Fig. 2, respectively, showing the end of the cable for attaching the package;

Fig. 4 is an end view of the same, looking 30 at the end adapted to be connected to the trailing end of the suspension cable;

Fig. 5 is a side view of the cable anchor or 35 trailer, showing the end of the cable;

Fig. 6 is an axial cross-section of the cable anchor; and

Fig. 7 is an end view thereof. 40 The package carrier or cable receiving means which may be in the form of a socket member 31 is similar in function to that described in said earlier application, wherein it is termed a "socket" member, having a flared open socket or anchor receiving end and a closed end provided with a central aperture 32 and a slot 33 along one side from the flared end to the aperture to receive the suspension cable when the anchor is drawn into 45 it for picking it up.

The opposite end of the carrier or receiving member is provided with a projecting recess providing anchor retaining means which may be composed of spring fingers 34 preferably formed by slitting its side walls, as

shown in Figs. 1, 2 and 4. This recess is adapted to receive and hold the anchor or suitable cooperating member 35, which is advantageously made in the shape of a ball, and to which the suspension cable 36 is attached in any suitable way. Preferably the cable 36 is provided with a swivel connection with the anchor, as by the hardened steel bushing 37 or similar means secured in the anchor in any suitable way. In the embodiment of the invention shown, the bushing is secured by being screwed into an axial bore in the anchor and the cable passes loosely through it and has its end fitted with a thimble 38 adapted to seat in the bushing and to 55 rotate therein.

The opposite end of the bore in the anchor is closed by suitable means shown as a plug 39, slightly tapered to adapt it to project into the aperture in the closed end of the carrier and steady the anchor when the latter is seated in the spring recess, as shown in dotted lines in Fig. 2.

The strength of the spring fingers 34 is sufficient to retain the cooperating member in 75 place during the lowering of the carrier from the plane, but insufficient to withstand the shock of contact with the ground apparatus, when it lets go and permits the carrier to remain in the hopper, as described in said 80 earlier application.

A flexible cable 40 is secured to a lug 41 on the side of the carrier opposite the slot 33, to which the package is attached.

The device is strong and durable in its construction, and does not require special tools for manipulating it. Obviously variations may be made in the shape and construction of the various parts, and the invention is not restricted to the construction illustrated. 85

I claim the following as my invention: 90

1. A two part attachable connection for the carrier and suspending cable of an airplane transfer apparatus comprising an elongated receiving member adapted to receive a cooperating member from either direction, and a spring seat on one end of the receiving member for the cooperating member, said receiving member having means for passing the cable therethrough when the co- 95

- operating member is engaged in one of its cooperating positions.
2. A two part attachable connection for the carrier and suspending cable of an airplane transfer apparatus comprising an elongated receiving member adapted to receive a cooperating member from either direction, a spring seat on one end of the receiving member for the cooperating member, a swivel between said cooperating member and the suspension cable, and means for admitting and passing the cable through said receiving member when the cooperating member is engaged in one of its cooperating positions.
3. A grapple for airplane package transfer apparatus comprising a tubular receiving member having an open end and a closed end with an aperture adjacent thereto and having a slot in the side wall of the receiving member extending from the open end to the aperture, a spring seat on the closed end of the receiving member, and a trailing connector adapted to be attached to the airplane and provided with a terminal fitting adapted to enter the open end of said receiving member and seat within its closed end to pick it up and also adapted to engage and be retained in said spring seat to lower said receiving member.
4. A grapple for airplane package transfer apparatus comprising a tubular receiving member having an open end, a closed end, an aperture adjacent to the closed end and a slot in the side wall of the receiving member extending from the open end to the aperture, a spring seat on the closed end of the receiving member, and a trailing connector adapted to be attached to the airplane and provided with a ball swiveled thereto adapted to enter the open end of said receiving member and seat within its closed end and also adapted to engage and be retained in said spring seat.
5. A grapple for airplane package transfer apparatus comprising a suspension cable, and associated receiving member having an open end and a closed end, a spring seat on the closed end, said receiving member having an aperture to receive said cable when the anchor is seated within its closed end, and an anchor for the suspension cable, said anchor being adapted to enter the open end of said receiving member or to be seated in said spring seat.
6. A grapple for airplane package transfer apparatus comprising a suspension cable and a cable receiving member having an open end and a closed end, a spring seat on the closed end, and an anchor for the suspension cable, said anchor being adapted to enter the open end of said receiving member or to be seated in said spring seat, said receiving member having an aperture to receive said cable when the anchor is seated within its closed end, said anchor having a projection in alinement with said cable adapted to enter said aperture when seated in said spring seat.
- In testimony whereof, I have signed my name to this specification.
